Patented June 27, 1922.

WITNESS:

Al Stark.

INVENTOR:

CHARLES F. SPERY,

Richard Stark & Son,
ATTORNEYS.

UNITED STATES PATENT OFFICE.

CHARLES F. SPERRY, OF CHICAGO, ILLINOIS.

RADIATOR FOR EXPLOSIVE ENGINES.

1,420,878.

Specification of Letters Patent. Patented June 27, 1922.

Application filed November 7, 1919. Serial No. 336,332.

To all whom it may concern:

Be it known that I, CHARLES F. SPERRY, a citizen of the United States, and resident of the city of Chicago, in the county of

5 Cook and State of Illinois, have invented certain new and useful Improvements in Radiators for Explosive Engines; and I do hereby declare that the following description of my invention, taken in connection 10 with the accompanying sheet of drawings, forms a full, clear, and exact specification, which will enable others skilled in the art to which the said invention appertains to make and use the same.

15 This invention has general reference to improvements in radiators for internal combustion engines; and it is especially addressed to the water tubes employed in these radiators. It consists, essentially, in the 20 novel and peculiar combination of parts and details of construction, as hereinafter first fully set forth and described, and then pointed out in the claims.

The object of this invention is the production of an efficient and serviceable core for radiators; and especially that type of radiators in which flat, straight, tubes surrounded by heat conducting fins are employed. In this type of water tubes difficulty is experienced in placing separate fins upon the tubes and retaining them in position until they are permanently attached to the tubes; and it is one of the purposes of 30 this invention to so construct the fins that they will adhere to the tubes with sufficient force to permit the tubes being readily handled without disturbing or dislocating the fins. To accomplish these desirable objects, I provide fins which are to a certain 35 degree expansible and resilient, and construct these fins in a manner that will cause the fins to stick tightly to the tube, even should the tube be somewhat irregular in shape or size, until the fins are permanently 40 attached to the tube by soldering.

In the drawings forming a part of this specification and illustrating this invention quite fully—

Figure 1 is a side elevation of a water 50 tube provided with my improved heat conducting fins. Fig. 2 is a sectional plan of the same on line 2—2 of Fig. 1. Fig. 3 is a sectional plan view of one of the fins, on line 3—3 of Fig. 2, the tube being omitted 55 in this figure. Fig. 4 is a side elevation of a fragment of a water tube and one of the

fins, illustrating a slight modification of the fin. Fig. 5 is a side elevation of a pair of water tubes provided with a series of twin-fins; and Fig. 6 is a plan of the same. Fig. 60 7 is an end elevation of a pair of tubes provided with a twin fin; and Fig. 8 is a plan of the same. Fig. 9 is a plan of a round water tube provided with a circular fin constructed in accord with my invention. 65

Like parts are designated by the same characters and symbols of reference in all the figures.

A, in the drawings designates the tube; and B, the heat conducting fins thereon. 70 This tube is of any desired design, preferably of elongate ovate transverse contour, having flat, parallel sides 12, and rounded ends 13. This tube may be a seamless drawn tube, or formed from strips of metal 75 and lock seamed. In the latter case, which is probably the most prevalent method of producing these tubes on account of cheapness, they are not perfectly uniform, so that there is considerable difficulty experienced in making the fins stick to the 80 tube until permanently attached thereto, owing to the fact that the openings in the fins, which are punched therein by suitably constructed dies, are practically uniform in 85 size, may fit some portions of the tube rather loosely and are, therefore, liable to shift out of their proper position.

The fins B, are made from thin sheet metal, and are likewise of elongate ovate 90 contour having parallel sides 14, and rounded ends 15. These fins are punched each with an oblong hole 16, corresponding approximately to the outer contour of the tube A, the inner margins of the fin being slightly 95 beveled, as at 17, the object of which will hereinafter appear. These holes are slightly shorter than the width of the tube, and in the parallel sides of these fins there are formed corrugations 18, which are sufficiently 100 pronounced to render these fins longitudinally expansible and resilient, so that when the fins are forced upon the tube, they will slightly elongate and owing to their resiliency have a tendency to contract and to 105 stick so tightly to the tubes that the tubes can be easily handled without disturbing the position of the fins upon the tubes. And in order to permanently affix these fins to the tubes, I proceed, as follows:

I first place the tubes into a fluxing solution, and then dip the tubes into a bath of

molten solder to give them an outer, substantial coating of solder. I now properly locate the fins upon the tubes, then dip them in a fluxing solution, and finally subject the 5 whole to heat sufficient to melt the solder which in its fluid condition, aided by the flux, will flow into the minute grooves 19, formed at the junction of the fins with the tubes by the slight beveling 17 of the inner 10 margins of the fins, so that when the solder has solidified, these fins are integrally connected to the tubes, at the same time giving to the whole a protective metallic coating of solder, whereby I am enabled to make the 15 tubes and fins of a ferric metal if desired, which will cheapen the cost of the tubes without seriously affecting the efficiency of the tubes and the heat conductors.

In order to still further reduce the cost of 20 manufacturing the water tubes, I make the fins in connected multiples; and in Fig. 5, I have illustrated a pair of water tubes provided with twin fins, which are suitable for employment in radiator cores wherein rows 25 of tubes are placed fore-and-aft, or behind each other so as to correctly space the tubes; and in Figs. 7 and 8, I show tubes having twin fins which space the tubes positively alongside of each other. The advantages 30 derived by thus forming multiple fins are that their cost of production is no more than that of single fins, and that the tubes are positively spaced apart and cannot be disturbed in their position by the jars and jolts 35 to which a radiator when mounted upon a motor driven vehicle, is always subjected to.

In certain radiators wherein plain round tubes Aa, Fig. 9, are preferred and surrounded by circular fins Bb, provide these fins 40 with radially extending corrugations 20, whereby these fins are rendered expandable and resilient in several directions and thereby enabled to hug the tube Aa snugly until they are permanently secured thereto by my 45 method of dipping as hereinbefore described.

In the construction hereinbefore set forth, the fins B are expandable and resilient in the longitudinal direction only, which is, however, sufficient for all practical purposes; 50 but when desired, these fins can be made expandable and resilient in both, longitudinal and transverse directions, by corrugating the ends of the fins as shown at 21, and the sides thereof as at 22, Fig. 8.

55 Attention is now invited to the slight flaring edges of the inner margins of the fins which form, when assembled upon the tube, small depressions 19. These flaring edges form, as it were, slightly enlarged entrants 60 through which the tube may find its way into the fin, thereby slightly elongating the fins which owing to their resiliency will cause them to cling to the tube without any other assistance or means for holding them temporarily to the tube.

Having thus fully described this invention, I claim as new, and desire to secure to myself by Letters Patent of the United States—

1. A water tube for a radiator core, comprising, a tube having smooth exterior surfaces, and a series of heat conducting fins projecting laterally from said tube in spaced relationship, said fins being curved between their ends to make them expandable and said fins being resilient and adapted to be forced along the tube to their positions and to remain on the tube by the contractive force of the fins. 70

2. In a radiator for automobiles, a flat- 80 tened tube in combination with a thin sheet metal fin for placement on the tube, the fin having a centrally disposed elongated hole shorter than the width of the tube and the fin being curved laterally between its ends 85 whereby the said opening is adapted to be lengthened by flattening the fin as it is placed in position on the tube and is adapted to automatically engage the tube with a holding pressure when the flattening force 90 is removed.

3. A radiating fin for a water tube for an automobile radiator the fin being formed out of relatively thin sheet metal and provided with a central opening for receiving 95 a tube, the fin being distorted out of its plane in a transverse section crossing said opening whereby a dimension of the opening is made less than the similar dimension of the tube to which it is to be applied, the hole being adapted to be elongated in its shortened dimension by flattening the fin, and adapted to engage a tube with a holding pressure when the flattening force is removed. 100

4. The improvements herein described, comprising a flattened water tube for an automobile radiator, a fin made of relatively thin sheet metal for placement on the tube, the fin provided with a central elongated 105 opening substantially fitting the tube, the fin curved to one side at a part extending transversely of said opening for shortening the opening, the opening adapted to be elongated to permit the fin to be readily placed 110 in position on the tube by pressure tending to flatten the fin.

5. The improvements herein described comprising a relatively thin sheet metal fin for a water tube of an automobile radiator, the fin having a central opening of less dimensions than the tube at least in one direction and having a relatively narrow flange defining the periphery of the opening, the fin curved out of its plane at a point between its ends and transversely of said opening whereby when a flattening force is applied to the fin the opening is elongated permitting the fin to be readily placed upon a tube, the fin being resilient 120 125 130

and adapted to engage the tube with a holding pressure when the flattening force is removed.

6. In a radiator core, water tubes, twin sheet metal fins connecting pairs of water tubes, each fin having two openings one for each tube, the two parts of the fin curved out of its plane whereby the openings are reduced on one diameter, the fins 10 adapted to be placed upon the tubes by lat-

eral pressure which tends to elongate the openings and permit the ready placement of the fins, the fins being resilient and adapted to engage the tubes with a holding pressure when the lateral pressure is removed. 15

In testimony that I claim the foregoing as my invention, I have hereunto set my hand.

CHARLES F. SPERY.
